UNITED STATES PATENT OFFICE.

JAMES C. SHAW, OF PHILADELPHIA, PENNSYLVANIA, ASSIGNEE TO THE WILLIAM CHAMP & SONS SHIP & ENGINE BUILDING COMPANY, A CORPORATION OF PENNSYLVANIA.

COMPOUND GEARED TURBINE.

1,235,938.

Specification of Letters Patent. Patented Aug. 7, 1917.

Application filed April 11, 1916. Serial No. 90,296.

To all whom it may concern:

Be it known that I, JAMES C. SHAW, a citizen of the United States, residing at Philadelphia, in the county of Philadelphia 5 and State of Pennsylvania, have invented certain new and useful Improvements in Compound Geared Turbine Propulsion for Varying Powers, of which the following is a full, clear, and exact specification.

10 This invention relates to marine propulsion, and has for its object to provide a system of compounded geared turbines of separate high and low pressure units especially intended for the economical propulsion of 15 a very high powered vessel at both full and cruising speeds. In a vessel of very high power, it is necessary to provide for a plurality of economical cruising speeds, which are attained herein by subdividing the high 20 and low pressure turbines and their connections so that they can be variously grouped or easily cut out according to the speed desired. It is also desirable to divide a large power between several pinions meshing with a common gear on the propeller 25 shaft, so as to reduce the power transmitted per pinion to a safe value, and also to save weight by reducing the number of gears required per vessel relatively to the total 30 power to be developed.

There is shown herein one propulsion unit embodying a propeller shaft carrying a large gear and driven through pinions from a plurality of turbine shafts and high 35 and low pressure units. By this invention various turbine units and pinions may be interchangeable, owing to the development of equal powers on different pinion shafts 40 geared to the propeller shaft. One or more of such propulsion units may be used, as may be desired.

As the power of a warship increases, it becomes more and more desirable to subdivide the low pressure end of the turbine 45 system into several units, because thereby the best economy is obtained at high vacuums, and also because of enabling better and stronger blading structure to be provided. Conversely it is desirable to develop 50 low powers with a few of the units running under high efficiency, with the remaining units idle, than to attempt to run all of the units under partial load and necessarily reduced efficiency. It is also desirable in large 55 powers to keep the units as small as possible,

and to make similar units rotate in the same direction so that they become interchangeable, all of which is obtained in the present invention.

In the accompanying drawing, 60

Figure 1 is a plan view, and showing the gears in section on the line 1—1 of Fig. 3;

Fig. 2 is a side elevation and

Fig. 3 is an elevation showing section 65 through gear box and the arrangement of the pinions relatively to the gear.

1 is a propeller shaft connected through a coupling to a double gear 2, which meshes with four pinions 3, 4, 5, 6. The pinions 5, 6, driven by the rear turbines 13, 14, are in 70 a horizontal plane above the horizontal plane including the pinions 3, and 4. The latter are connected to forwardly extending shafts, respectively, carrying a high pressure unit 7, a low pressure unit 8 in tandem driving pinion 3, and a high pressure unit 10 and a low pressure unit 11 in tandem driving the pinion 4. Reversing is effected by turbine 28 in the same casing 75 with low pressure turbine 8, and turbine 29 in the same casing with low pressure turbine 11. These turbines discharge through a trunk 26 to a condenser 27, while the turbines 13, 14, discharge through a trunk 39 to a condenser 37. The turbines 7, 8 and 80 28, are connected to the pinion 3 through a flexible coupling 9, while the turbines 10, 11 and 29 are connected to the pinion 4 through similar flexible coupling 12. The turbine 13 is connected to the pinion 5 85 through a coupling 15 and turbine 14 is similarly connected to the pinion 6 through a coupling 16.

The high pressure turbines 7 and 10 are 90 of identical design with all parts interchangeable, and take steam in parallel or independently from steam main 17 through pipes 18 and 19 controlled by valves 20 and 21. The turbines 8 and 11 are single flow low pressure units, alike in construction and 100 having all parts interchangeable. These receive steam from cross connected pipes 22, 23, controlled by valves 24, 25, so that the high pressure turbine on one driving shaft 105 exhausts to the low pressure turbine on the other shaft. The reversing turbines 28, 29, take steam in parallel, or separately, through pipe 30 and branches 31, 32. The turbines 13 and 14 are double flow low pressure turbines having their blading in each opposed 110

part identical with the blading in each single flow low pressure turbine 8, 11. The double flow low pressure turbines 13 and 14 are supplied respectively from each high pressure turbine on the same side through pipes 33, 34, controlled by valves 35, 36. The steam enters at the center of each of turbines 13 and 14 and flows in opposite directions, exhausting through the common condenser trunk 39 to condenser 37.

10 The turbines 7 and 10 preferably consist of one compound velocity wheel stage each, and the reverse turbines 28 and 29 of one or more compound velocity stages each, while the low pressure units 8, 11, and 13, 14, have either impulse or reaction blading of all wheel or all drum construction.

15 At full power, turbines 7 and 10 each pass one-half of the total steam, turbines 13 and 14 each one-third, and turbines 8 and 11 each one-sixth of the total steam. Also at full power, turbines 7, 10, and 8, 11, deliver each approximately one-eighth of the total power, and turbines 13 and 14 each one-fourth of the total power. As all of the 20 pinions operate at the same speed, and since the powers are equally divided among them, the pinions will be interchangeable, which is of advantage in that fewer spare parts are required to be carried either on the ship or 25 in stock at the yard.

30 At seven-eighths of full power, valves 24 and 25 will be closed, thereby allowing either turbine 8 or 11 to be revolved idly in the condenser vacuum. At three-fourths power, valves 24 and 25 will be opened, and valve 35 or 36 closed, thereby cutting out one of the double flow units 13 or 14, which will revolve in the condenser vacuum. At approximately one-half power, both of turbines 13 and 14 will be cut out by closing valves 35 and 36. If it is not desired to run the turbines 13 and 14 idle in the condenser vacuum, they may be disconnected 35 at couplings 15, 16, which will allow condenser 37 with its attendant auxiliaries to be shut down. This will result in a material saving in total steam required for propulsion and for auxiliary purposes, and will be 40 of especial value in very high powered, high speed naval vessels, which are operated much of the time at one-half speed or under. An alternate operation for half power is to employ one high pressure unit, one single 45 flow unit, and one double flow unit, but in time of peace, when the vessel would be operated for the greater part of the time at one-half and less than one-half power, it would be preferable to keep turbines 13 and 14 disconnected. At approximately one-fourth power and less, only one high pressure unit and one single flow low pressure unit would be used, the power being delivered through the two pinions 3 and 4. This 50 would also be the case in reversing. The ar-

range ment for one-quarter power and less is the one under which the vessel would be operated most, and by distributing the power on two pinions, their life is very much increased owing to the low working stresses.

70 It will be seen that at full power using all six turbines, at half power using turbines 7, 8, 10 and 11, and at one-fourth power using turbines 10 and 8 or 7 and 11, the powers on the propeller shaft gear will be balanced, 75 that is the same amount of power will be applied on each side by reason of the subdivision and cross connection of the several high and low pressure units. Also, at three-fourths power, in which turbines 8 and 11 are cut out, the powers on opposite sides of the propeller shaft gear will be balanced. It will also be seen that the turbine units 80 are much more interchangeable than in previous constructions, which is of decided importance in installations required to develop large powers, not only from the standpoint of spares required to be carried on board ship, but those required to be kept in stock at the yard. Thus, the turbines 7 and 10 are 85 alike and interchangeable. The turbines 8 and 11, and their reverse ends are respectively interchangeable, and also the turbines 8 and 11 are like each half of the double flow low pressure turbine units 13 and 14. 90

95 Thus, the four low pressure units are all practically interchangeable. Inasmuch as the shafts on each side run at the same speed the pinions are all interchangeable and owing to the division of the powers between the four pinions 3, 4, 5, 6, each can be made of ample strength, and not be subject to breakage by overload. Also, the present invention is of advantage because of the facility with which one or more of the units can be 100 cut out, and if necessary disconnected from the shaft, when the ship is to operate for an appreciable time at fractional power. There is also an advantage in this respect in having a condenser for the low pressure units 8 and 11 separate from that for the low pressure units 13 and 14, as this permits one set to be shut down entirely when there is to be a 105 prolonged run at one-half or less power.

110 Various modifications and changes may be 115 made in the form of the invention shown diagrammatically herein, within the scope of the appended claims.

Having thus described my invention, I declare that what I claim as new and desire 120 to secure by Letters Patent, is:—

1. In a marine turbine installation, a plurality of high pressure units adapted to operate in parallel, a plurality of low pressure units supplied by each high pressure unit, 125 said high and low pressure units being geared to a propeller shaft, and means for variably cutting out said low pressure units to obtain powers between one-half and seven-eighths.

2. In a marine turbine installation, a propeller shaft having a gear, a high pressure unit and two low pressure units arranged in tandem on each side of said gear and having driving connections therewith, and connections for equally varying the proportion of power applied to said gear by said sets of tandem units. 70
3. In a marine turbine installation, a propeller shaft having a gear, a high pressure unit and two low pressure units arranged in tandem on each side of said gear and having driving connections therewith, and connections controlling said low pressure units for equally varying the proportion of power applied to said gear by said sets of tandem units. 75
4. In a marine turbine installation, a propeller shaft having a gear, a high pressure unit and two low pressure turbines arranged in tandem on each side of said gear and having driving connections therewith, and means for connecting each high pressure turbine with one of its tandem low pressure turbines and to the remaining low pressure turbine of the other tandem set. 80
5. In a marine turbine installation, a propeller shaft having a gear, a high pressure unit and two low pressure turbines of unequal power arranged in tandem on each side of said gear and having driving connections therewith, and independent means for connecting each high pressure turbine with one of its tandem low pressure turbines and to the remaining low pressure turbine of the other tandem set, whereby to obtain powers varying according to which of said low pressure turbines is used. 85
6. In a marine turbine installation, a propeller shaft having a gear, a high pressure unit on each side for equally driving said gear, a low pressure unit in tandem with each high pressure unit for also equally driving said gear on opposite sides, a cross connection between each high pressure unit and the opposite low pressure unit, and controlling means for cutting out a high pressure unit and its connected low pressure unit to obtain reduced power. 90
7. In a marine turbine installation, a propeller shaft having a gear, a high pressure unit on each side for equally driving said gear, a low pressure unit in tandem with each high pressure unit and of equal power for also equally driving said gear on opposite sides, a cross connection between each high pressure unit and the opposite low pressure unit, and controlling means for cutting out a high pressure unit and its connected low pressure unit to obtain reduced power equally on both sides of the gear from the remaining high and low pressure units. 95
8. In a marine turbine installation, a propeller shaft having a gear, a high pressure unit on each side for driving said gear, a plurality of low pressure units in tandem with each high pressure unit for additionally driving said gear, and means for applying equal powers on each side of said gear. 100
9. In a marine turbine installation, a propeller shaft having a gear, a high pressure unit on each side for driving said gear, a plurality of low pressure units in tandem with each high pressure unit for additionally driving said gear, said high pressure units exhausting to said low pressure units, and means for applying equal powers on each side of said gear. 105
10. In a marine turbine installation, a propeller shaft having a gear, a high pressure unit on each side for driving said gear, a plurality of low pressure units in tandem with each high pressure unit for additionally driving said gear, and means for applying equal powers on each side of said gear at full and a plurality of partial powers. 110
11. In a marine turbine installation, a propeller shaft having a gear, a high pressure unit on each side for driving said gear, said high pressure units developing equal power, a plurality of low pressure units in tandem with each high pressure unit, one of said low pressure units on each side being of twice the power of the other, each high pressure unit being connected to two of said low pressure units in such manner that one low pressure unit on each side can be cut out without unbalancing the powers applied to said gear. 115
12. In a marine turbine installation, a propeller shaft having a gear, a high pressure unit of equal power on each side for driving said gear, a plurality of low pressure units on each side for also driving said gear, a connection from each high pressure unit to a low pressure unit on the other side, and a second connection from each high pressure unit to the remaining low pressure unit on the same side. 120
13. In a marine turbine installation, a propeller shaft having a gear, a high pressure unit of equal power on each side for driving said gear, a plurality of low pressure units on each side for also driving said gear, one of said low pressure units being of equal power to said high pressure unit, and the other low pressure unit being of twice the power, a connection from each high pressure unit to the small low pressure unit on the other side, and a second connection from each high pressure unit to the large low pressure unit on the same side. 125
14. In a marine turbine installation, a propeller shaft having a gear, a high pressure unit and a low pressure turbine unit on each side of said gear having driving connection therewith, and a second pair of low pressure units 130

each geared independently to said propeller shaft gear.

15. In a marine turbine installation, a propeller shaft having a gear, a high pressure and a low pressure turbine unit on each side of said gear having driving connection therewith, a series connection from each high pressure unit to the opposite low pressure unit, a second pair of low pressure units each geared independently to said propeller shaft gear, and means for supplying said latter low pressure units from said high pressure units.

16. In a marine turbine installation, a propeller shaft having a gear, a high pressure and a low pressure turbine unit on each side of said gear having driving connection therewith, and a second pair of low pressure units each geared independently to said propeller shaft gear in a different horizontal plane.

17. In a marine turbine installation, a propeller shaft having a gear, a high pressure and a low pressure turbine unit on each side of said gear having driving connection therewith, said high and low pressure units on each side developing substantially one-eighth power each, a second low pressure unit on each side independently geared to said propeller shaft gear and developing approximately one-fourth power.

18. In a marine turbine installation, a propeller shaft having a gear, a high pressure and a low pressure turbine unit on each side of said gear having driving connection therewith, said high and low pressure units on each side developing substantially one-eighth power each, and a second low pressure unit on each side independently geared to said propeller shaft gear, said latter low pressure unit being each of divided flow type and having each half interchangeable with said first mentioned low pressure units.

19. In a marine turbine installation, a propeller shaft having a gear, a high pressure and a low pressure turbine in tandem on each side of said gear and having driving connections therewith, a condenser connected to said low pressure units, a second low pressure unit on each side geared to said propeller shaft gear, and a second condenser for each of said latter units.

20. In a marine turbine installation, a propeller shaft having a gear, a high pressure and a low pressure turbine in tandem on each side of said gear and having driving connections therewith, a condenser connected to said low pressure units, a second low pressure unit on each side geared to said propeller shaft gear, a second condenser for each of said latter units, and means for discon-

necting said latter low pressure units and their condenser at reduced power.

21. In a marine turbine installation, a plurality of high pressure units adapted to operate in parallel and each to pass one-half the total volume of steam, a plurality of low pressure units each in tandem location with one of said high pressure units and each being connected in series to the other high pressure unit, a propeller shaft having a gear and pinions driven by said tandem units meshing with said gear, whereby equal power is applied to said gear on each side when all of said units are working, or at reduced power with one high pressure and its connected low pressure unit cut out.

22. In a marine turbine installation, a plurality of high pressure units adapted to operate in parallel and each to pass one-half the total volume of steam, a plurality of low pressure units each in tandem with one of said high pressure units and each being connected in series to the other high pressure unit, a propeller shaft having a gear, and pinions driven by said tandem units meshing with said gear, whereby equal power is applied to said gear on each side when all of said units are working, or at reduced power with one high pressure and its connected low pressure unit cut out, a second low pressure unit on each side geared to said propeller shaft gear, each of said second low pressure units developing a power equal to that of each high pressure unit and its connected low pressure unit.

23. In a marine turbine installation, a propeller shaft having a gear, a high pressure and a low pressure unit arranged in tandem on each side of said gear and having driving connections therewith, and a reverse turbine associated with each of said low pressure units.

24. In a marine turbine installation, a propeller shaft having a gear, a high pressure and a low pressure unit arranged in tandem on each side of said gear and having driving connections therewith, a reverse turbine associated with each of said low pressure units, and a condenser common to said two low pressure units and said reversing turbines, the low pressure unit on one side being in series with the high pressure unit on the other side.

In testimony whereof I affix my signature in presence of two witnesses.

JAMES C. SHAW.
